GRINDING DISC SEGMENT

Ake Sandstrom, Falkvagen 65, Taby, Sweden

Filed July 19, 1971, Ser. No. 164,216

Claims priority, application Sweden Jan. 20, 1971

Term of patent 14 years

Int. Cl. D15—09

U.S. Cl. D37—1 R

FIG. 1.

FIG. 2.

FIG. 1 is a front elevation of a grinding disc segment embodying my design.

FIG. 2 is a section taken on line 2—2 of FIG. 1.

The back of the grinding disc segment is plain.

I claim:

The ornamental design for a grinding disc segment, as shown and described.
